United States Patent Office.

CHRISTOPHER MOEGLING, OF MILWAUKEE, WISCONSIN.

Letters-Patent No. 72,317, dated December 17, 1867.

IMPROVED VENTILATOR FOR FLOUR-MILLS.

The Schedule referred to in these Letters Patent and making part of the same.

TO WHOM IT MAY CONCERN:

Be it known that I, CHRISTOPHER MOEGLING, of Milwaukee, have invented new and useful Improvements in Flour-Mills; and I do hereby declare the following to be a full and exact description of the same, reference being had to the drawings that accompany and form a part of these specifications, in which—

Figure 1 is a perspective view, with a portion of the curb broken off, showing the parts attached to the running-stone.

Figure 2, sectional view, with outlines of the educting-pipe on the left.

Figure 3, sectional view of the educting-pipe, with device for catching the water that may trickle down on the inside of the pipe.

Letter A, the running-stone; letter B, the curb; letter C, the conveyer or receptacle for the flour; letter D, pipe for carrying off the moisture; letter E, wings in the side of the stone; letter F, frame to prevent flour from gathering between the running-stone and the curb; letter g, slots in the face-flange of the wings E, for adjusting the angle it shall have upon the stone; letter h, slots in the frame F, for adjusting it vertically; letter i, a stop or preventive to the passing of cold air over the top of the stone to the flour, and also to the issuing of the heated air, bearing dust and moisture into the mill; j, outlet for the flour; k k, shelves in the educting-pipe D, to stop the water that may condense in the interior of this pipe; l, spout to take off the water; O, slide, opening into the spout D; m represents a device built upon the stone, or fastened thereto, and rising to the under side of the top of the curb, shutting off the communication with the space around the periphery of the stone; n, a rim of rubber, leather, or other suitable material, lying across from stone to side of curb—a method of closing the space or cutting off the communication, that may be adopted if found more convenient, fastened either to the curb or to the stone.

The object of my invention is to provide not only a cooling-device for the flour before it goes to the bolt, but, also, a device that shall evaporate the moisture, and produce a drying-process; this latter being by far the most important to the manufacture of good flour. Indeed, we think a cooling-process simply is of no practical advantage whatever, for the cooling only condenses the moisture, which is always abundant, leaving it in the flour, making it damp, so it bolts poorly, clogging the bolt-cloth, causing it to rust and decay rapidly, while less flour is obtained, as much adheres to the bran.

Now, my plan is to take away the moist air before any cold air can reach it to condense the moisture. I accomplish this by closing up the space between the top of the running-stone and the inside of the curb. This is done in various ways: by a band of leather, rubber, or any other suitable material, hanging from the under side of the top of the curb, and reaching to the top of the running-stone, as i, in fig. 1, or the device may be built up upon the stone, as represented at m, in fig. 2; or, if more convenient, a disk or other suitable closing-device may be arranged, to lay across from the stone to the curb, as represented by n, in fig. 2.

It is well known that as the running-stone revolves rapidly, a current of air is thrown off from the periphery.

I provide for the passage or escape of the air around the stone, which is warm, and carrying much moisture, by leading off a tube or pipe, either from some part of the curb itself, or from the receptacle into which the flour falls in leaving the stones.

Having provided for carrying away the air that contains the moisture and other impurities, I can now let in cool air without making the flour damp and clammy. Having shut up the space between the curb and stone, as hereinbefore set forth, the cool air passes down through the eye of the upper stone and along the grinding-surfaces of the stone, preventing heating, causing a purer grinding than can possibly be obtained with closing the space over the top of the stone.

In addition to closing the space, as above mentioned, wings E may be used, more or less in number, on the periphery of the stone. These wings have slots in them, by which the angle they shall have may be regulated.

To prevent any flour from remaining between the stones and the curb, when the wings E are not used, the frame F, or two of them, may be used; or, if desired, these may be used as well as when the wings are.

To prevent any water, that may condense in the interior of the pipe D, from running down into the flour, I place the inclined plates or shelves k k, as in fig. 2; or a circular convex disk, as represented by h, in fig. 3.

It is not necessary to use the wings E, nor do I, when using them, confine myself to any particular form of them.

I am aware that various devices for shutting off the air from going over the top of the stone have been adopted, but they have been by closing up the usual opening in the top of the curb. This has been objectionable to millers, as they have been so long accustomed to look to running-stone through this opening, to observe if it were running truly, that they do not like to have the curb covered.

I allow all and even more than the usual opening, and I do not confine myself to any particular place of forming cut-off i. It may be as represented at i, in fig. 1, or by m, in fig. 2, or by n, as in fig. 2, or in any manner to make a suitable stop for the passage of the air, while leaving the top of the curb free and open.

If the draught of the pipe D should, for any reason, not be sufficient, a fan or any other device to increase it, may be used at its upper end, or at any other suitable place, for effecting the object sought, and carry off the moisture, without taking away any of the flour.

What I claim as of my invention, and desire to secure by Letters Patent, is—

1. In connection with an ordinary open-top curb, the stops i, m, or n, or their equivalent, as and for the purposes set forth.

2. I claim the educting-pipe D, when provided with the water-stops k k, or k', whether said pipe leads off from the curb B, or from the receptacle C, for the purposes specified, either with or without the aid of the wings E.

3. I claim the vertically adjustable frame F, when used as and for the purposes specified.

In testimony whereof, I have signed my name to this specification, in the presence of two subscribing witnesses.

CHRISTOPHER MOEGLING.
